[57] CLAIM

The ornamental design for a lawn edging system, as shown and described.

DESCRIPTION

FIG. 1 is an exploded perspective view of a lawn edging unit shown in FIG. 26 showing my new design;

1 Claim, 11 Drawing Sheets

FIG. 2 is a front view of the main portion thereof;
FIG. 3 is a rear view thereof;
FIG. 4 is a top view thereof;
FIG. 5 is a bottom view thereof;
FIG. 6 is a left side view thereof;
FIG. 7 is a right side view thereof;
FIG. 8 is a front view of the end piece portion thereof;
FIG. 9 is a rear view thereof;
FIG. 10 is a left side view thereof;
FIG. 11 is a right side view thereof;
FIG. 12 is a top view thereof;
FIG. 13 is a bottom view thereof;
FIG. 14 is a left side view of the outside curve portion thereof;
FIG. 15 is a front view thereof;
FIG. 16 is a rear view thereof;
FIG. 17 is a right side view thereof;
FIG. 18 is a top view thereof;
FIG. 19 is a bottom view thereof;
FIG. 20 is a left side view of the inside curve portion thereof;
FIG. 21 is a front view thereof;
FIG. 22 is a rear view thereof;
FIG. 23 is a right side view thereof;
FIG. 24 is a top view thereof; and,
FIG. 25 is a bottom view thereof; and,
FIG. 26 is a reduced perspective view of a lawn edging unit in fully assembled form.

The elements of the claimed design are shown detached for clarity of illustration.
